Attorney

UNITED STATES PATENT OFFICE.

GEORGE W. CONLEY, OF WHEATON, ILLINOIS.

TOBACCO-PIPE.

1,213,156.

Specification of Letters Patent. Patented Jan. 23, 1917.

Application filed March 27, 1916. Serial No. 87,035.

To all whom it may concern:

Be it known that I, GEORGE W. CONLEY, a citizen of the United States, residing at Wheaton, in the county of DuPage and State of Illinois, have invented certain new and useful Improvements in Tobacco-Pipes, of which the following is a specification, reference being had to the accompanying drawings.

10 This invention relates to tobacco pipes and has particular reference to improvements in stems therefor.

The principal object of the invention is to provide a stem which will prevent the accumulation of moisture therein, either saliva from the smoker's mouth or nicotin from the tobacco to thus keep the stem dry and provide for a free passage of the smoke therethrough.

20 Another object of the invention is to provide a stem of this character which will be thoroughly reliable and efficient in use and which will be simple in construction and cheap to produce.

25 With the foregoing and other objects in view, the invention consists in the novel features of construction, combination and arrangement of parts as will be hereinafter more fully described, illustrated in the accompanying drawings and claimed.

30 In the accompanying drawings, Figure 1 is a vertical longitudinal section of a tobacco pipe having a stem constructed in accordance with the invention. Fig. 2 is a transverse section on the line 2—2 of Fig. 1. Fig. 3 is a similar section on the line 3—3 of Fig. 1.

Referring to the drawings by numerals wherein is illustrated the preferred embodiment of my invention 1 designates the bowl of the improved pipe which is provided with the usual stem 2 having the mouthpiece 3 threaded therein, the stem being provided with an internal threaded recess to receive 45 the external threaded projection 4, of the mouthpiece whereby the two are connected. The stem is provided in the usual manner with an opening or passageway 5 which opens at one end into the bowl 1 and at its 50 opposite end at a point approximately centrally of the threaded recess. The mouthpiece is likewise provided with a longitudinally extending opening or passageway 6 which is adapted to align with the passageway 5 when the mouthpiece is connected with the stem, the said passageway 6 open-

ing at either end through the ends of the mouthpiece.

At its inner end, that is, the end having the extension 4 thereon, the mouth piece 3 is provided with an enlarged opening 7 which forms a continuation of the passageway 6. By reference to Fig. 1 of the drawings it will be noted that this enlarged opening has its upper wall arranged substantially in 60 alinement with the upper wall of the passageway 6 and has its lower wall extending a considerable distance below the lower wall of the said passageway. A chamber is thus provided below the passageway 6 adjacent 70 this end of the mouthpiece which is indicated at 8, the said chamber being separated from the passageway 6 by means of a perforated partition 9, which extends transversely and longitudinally of a preferably 75 metallic tube 10 arranged within the opening. The openings within the perforate partition 9 are each of a diameter materially less than the diameter of the opening or passageway 5. It is to be noted that the tube 80 terminates at its outer end in the plane of the outer end of the projection 4, and that when the mouthpiece is engaged with the stem, the outer end of the chamber 8 is closed by reason of the fact that the outer end of 85 the tube is arranged in abutting relation with the wall of the stem, the passageway above the partition 9 being alined with the passageways 5 and 6 to form a continuation 90 of the stem. At its outer end the mouthpiece is provided with a second enlarged opening 11 which is located below the passageway 6 in a manner similar to the opening 7, and this opening 11 has arranged therein a tube 12 which is similar in construction 95 to the tube 10 being provided with a perforated partition 13, extending horizontally and transversely thereof so as to provide a passageway 14 to form a continuation of the passageway 6 and a chamber 15 arranged below such passageway. The openings in the perforate partition 13 are also each of a diameter materially less than the diameter of the opening or passageway 6. The outer end of this tube 12 opens through the outer 100 end of the mouthpiece and is closed by means of a plug or stopper 16, the partition 13 being cut away adjacent the outer end of the tube to permit of insertion of this plug as will be understood.

110 It is desired to point out that the tubes 10 and 12 may be secured within the open-

ings 7 and 11 in any desired manner, the preferred way, however, being to merely slidably arrange the tubes within the openings so that they may be readily removed when desired, and since there will be no friction or forces acting to move the tubes or rotate the same, their frictional engagement with the openings will be sufficient to retain the same in place.

10 The passageway 6 intermediate the ends of the mouthpiece is deflected upwardly as indicated at 17 so that a portion thereof will extend downwardly toward the tube 10 while the remaining portion will extend 15 downwardly toward the tube 12. The upper wall of the tube 12 is provided with a transverse opening which is alined with a similar opening 18 in the mouthpiece to provide an exit for the smoke passing through 20 the passageway, and from the bowl when the outer end of the tube is plugged by means of the stopper 16.

From the foregoing description taken in connection with the accompanying drawings, the operation and advantages of the improved mouthpiece will be clearly understood. By arranging the opening 18 at right angles to the passageway 6 as is shown, and by positioning this opening at the top of 25 the mouthpiece, the liability of saliva entering the passageway from the smoker's mouth is reduced to a minimum. In the event, however, that saliva does find its way through this opening and into the passageway, it will instead of clogging the passageway pass through the perforated partition 30 13 and into the receiving chamber 15 which chamber may be readily cleaned by removing the same from the mouthpiece and if desired by removing the plug 16 therefrom, the downwardly extending portion of the passageway 6 from the upwardly deflected portion 17 serving to prevent any saliva or moisture from passing toward the inner end 40 of the stem. The partitions 13 serve as an effective medium to prevent the smoke passing through or within the openings 7 and 11 or opening 11 from coming into contact with the moisture or nicotin collected within the chambers 8 and 15 whereby the smoke when drawn into the mouth is substantially dry. It is thought to be self-evident that if the partitions 9 and 13 were omitted the eddies created as the smoke passes through 45 the passageways 5 and 6 would cause the smoke to be saturated by the moisture or the like collected within the chambers 8 and 15.

The operation of the tube 10 is similar to 50 that of the tube 12. Any nicotin or moisture passing through the opening 5 will pass through the perforated partition 9 and into the chamber 8, and by removing the mouth-

piece from the stem, the tube 10 may be readily removed for cleaning purposes, such 55 nicotin or other moisture from the tobacco being prevented from passing beynd the deflected portion 17 of the passageway 6 by reason of the downward arrangement of 60 this passageway toward the tube 10 from such deflected portion.

From the foregoing description taken in connection with the accompanying drawings it is thought that the construction, operation and advantages of the improved tobacco pipe will be clearly understood and while I have herein shown and described 75 one specific embodiment of my invention, I do not wish to be limited thereto except for such limitations as the claims may import. 80

Having described my invention what I claim is:

1. A tobacco pipe including a bowl and a stem, said stem being provided with a longitudinally extending passageway, said 85 passageway being enlarged adjacent its ends, tubes arranged within said enlarged portions of the passageway, perforated partitions extending longitudinally of said tubes to provide passageways and receiving chambers, the openings of the perforate partition being each of a diameter less than the diameter of the passageway, said second named passageways being disposed in communication with the first-mentioned passageway 90 and said receiving chambers being located below said first-mentioned passageway.

2. A tobacco pipe including a bowl and stem, said stem being provided with a longitudinally extending passageway, said 100 passageway being deflected upwardly intermediate its ends, one end of said stem being provided with an enlarged opening forming a continuation of the passageway, a tube arranged within said opening, a perforated 105 partition arranged transversely of said tube to provide a passageway and a receiving chamber, the perforations of the partition being each of a diameter less than the diameter of the passageway, said passageway being arranged in communication with said first-mentioned passageway, said partition being terminated short of the outer end of the tube, a stopper arranged within said tube, said stem being provided with a transverse opening, said tube being provided with an opening to be alined with said transverse opening to provide an opening in one side of the stem for the passage therefrom of smoke passing through the passageways. 110

In testimony whereof I hereunto affix my signature in the presence of two witnesses:

GEORGE W. CONLEY
